NOZZLE

Charles H. Jarvis, Battle Creek, Mich., assignor to
United Steel and Wire Company, Battle Creek,
Mich.

Original application October 3, 1932, Serial No.
635,891. Divided and this application March
23, 1933, Serial No. 662,208

8 Claims. (Cl. 299—132)

The present case is a division of my pending application Serial No. 635,891, filed October 3, 1932, for Atomizers or sprayers.

The main objects of this invention are:

5 First, to provide an improved nozzle for use with atomizers or sprayers of the type disclosed in my pending application referred to above and the like.

10 Second, to provide a nozzle for delivering a fine direct stream or jet of fluid such as water.

Third, to provide a nozzle of this character which is simple and efficient and is capable of fine adjustment and accurate regulation.

15 Fourth, to provide a nozzle of this character having its parts readily accessible for adjustment, replacement and renewal.

Further objects and objects pertaining to details and economies of construction and operation will appear from the detailed description to 20 follow. A preferred embodiment of my invention is illustrated in the accompanying drawing, in which:

Fig. 1 is a fragmentary side elevation of a spray unit embodying the features of my invention, 25 portions being shown in section and partially broken away.

Fig. 2 is an enlarged fragmentary vertical section through the nozzle assembly or unit, the valve being shown in full lines.

30 In the embodiment illustrated by the accompanying drawing, I provide a vertical supply pipe 1 which constitutes a supporting standard. On the upper end of the pipe 1 is a coupling head 2 having a cylindrical enlarged portion 3 embraced

35 by and constituting a support for the casing 4 which may be omitted if desired. The head is provided with an upwardly facing central socket 5 having an outlet or drain passage 6 discharging within the casing 4. The tubular support 7 is threaded into the socket 5 and it is provided

40 with a longitudinal drain slot 8 at its upper end. An atomizing disk 9 is seated upon the upper end of the drain pipe and has a depending central stem 10 which is seated within the pipe for 45 positioning and retaining the disk. The sleeve-like combined drain cup and baffle member 11 is threaded upon the support 7 for substantially longitudinal adjustment thereon, the upper or cup-like portion 12 of this member surrounding the

50 atomizing disk and spaced in concentric relation thereto. This combined baffle and drain member collects the unatomized water particles and the larger particles according to its adjustment relative to the impact or atomizing disk delivering 55 them to the drain pipe through the passages and

the openings described. By adjusting this member 11 relative to the impact or atomizing disk, the character of the spray is controlled. In its extreme upper position only the very finely divided or atomized spray is delivered from the top of the baffle member.

The head 3 in the embodiment illustrated is provided with a pair of upwardly facing socket members 13 and 14, the socket 13 being connected to the supply pipe 1 by a passage 15. Bowed arms 16 and 17 are mounted in these sockets to provide a yoke-like support for the T-shaped body member 18 of the spray nozzle, the arm 16 constituting a water supply conduit. The body member 18 has a cylindrical externally threaded portion 19 receiving the packing gland 20.

A valve carrying member 21 having a stepped bore is removably arranged within this tubular or cylindrical portion 19 of the nozzle body member and has an outwardly extending flange 22 at its outer end which engages the end of the body member when it is forced into position by the packing ring 23 disposed within the gland. The outer and larger portion 24 of the bore of this valve carrying member is internally threaded 70 to receive the externally threaded tubular nozzle member 25.

I provide a needle valve 26 having a stem 27, the upper end of which is frictionally mounted in the reduced bore 28 at the inner end of the valve carrying member, the lower end of which is provided with an enlargement or flange 29 having a groove 30 therein. At its inner end the valve carrying member has a passage 31 communicating with the interior of the body member 18.

The nozzle 25 extends through the opening 32 in the packing gland and is embraced by the packing. This nozzle has a bore 33 constituting a centering bearing or support for the needle valve 26 head 29. At the outer end of its bore 33 the nozzle member has a transverse partition 34 with a central port 35 with which the needle valve 26 coacts. Below this partition the nozzle member has an enlarged chamber 36 terminating in a flared mouth 37 so that the stream or jet is projected from the nozzle without contacting with any part and is effectively protected. The jet may be varied by adjusting the nozzle to open or close the needle valve.

The valve is effectively held in central or concentric relation relative to the walls of the nozzle port so that a perfect stream or jet is discharged and one that is properly directed to strike centrally of the atomizing disk. The distance be-

105

110

tween the top of the disk 9 and the nozzle is substantially fixed and the volume of water delivered by the jet is controlled by adjusting the nozzle, whereas the character of the spray delivered by the atomizing disk is controlled by adjusting the cup-like baffle member 12.

The spray may be so finely atomized as to constitute a fog-like mist which forms and maintains a blanket of cool moist air above the vegetables or fruit when the device is used in that relation, and it is found to very materially reduce the temperature within a substantial area. It is also found that equipment having my improvements embodied therein is highly effective in keeping vegetables and similar green products displayed in stores in a fresh desirable condition.

The apparatus has the very material advantage of effectively maintaining such a condition with a minimum of water so that the structure 20 is very economical to operate from that standpoint.

I have embodied my invention in a structure which has been found very satisfactory in use. I have not attempted to show other adaptations of 25 which my invention is capable, as it is believed this disclosure will enable the adaptation thereof by persons skilled in the art.

Having thus described my invention, what I claim as new and desire to secure by Letters Patent 30 is:

1. In a nozzle, the combination of a chambered body member having an externally threaded cylindrical portion, a tubular valve carrying member removably fitting within said cylindrical portion of said body member and having a flange at its outer end engaging the outer end of said cylindrical portion of said body member, a tubular nozzle member threaded for adjustment in said valve member and having a transverse partition spaced from its outer end and provided with a central port, a needle valve having a stem fixedly mounted at its inner end in said valve carrying member and provided with a disk-like head within said valve carrying member and in supporting engagement with the walls of said nozzle member within said cylindrical portion of the body member whereby the valve is supported in central relation relative to said port and to said cylindrical portion, said head being notched to provide a passage for water, said valve carrying member having a passage communicating with the interior of said body member, and a packing gland embracing said nozzle and threaded upon said cylindrical portion of said body member for holding 55 said valve carrying member in place.

2. In a nozzle, the combination of a chambered body member, a tubular valve carrying member fitting within said body member, a tubular nozzle member threaded for adjustment in said valve carrying member and having a transverse partition spaced from its outer end and provided with a central port, and a needle valve having a stem fixedly mounted at its inner end in said valve carrying member and provided with a head within said valve carrying member and in supporting engagement with the walls of said nozzle member within said body member whereby the valve is supported in central relation relative to said port and to said cylindrical portion, said head being notched to provide a passage for water, said valve carrying member having a passage communicating with the interior of said body member.

3. In a nozzle, the combination of a chambered body member, a valve carrying member disposed within said body member, a nozzle member

mounted in said valve carrying member and having a central port, and a needle valve having a stem fixedly mounted at its inner end in said valve carrying member and provided with a head within said valve carrying member and in supporting engagement with the said nozzle member within said body member whereby the valve is supported in central relation relative to said port and to said cylindrical portion, said head being notched to provide a passage for water, said valve carrying member having a passage communicating with the interior of said body member.

4. In a nozzle, the combination of a tubular body member, a chambered valve carrying member removably fitting within said body member and having a flange at its outer end engaging the outer end of said body member, a needle valve having a stem fixedly mounted at its inner end in said valve carrying member and terminating at its outer end within said valve carrying member and in an enlargement provided with a longitudinal passage, and a chambered nozzle threaded within said valve carrying member and having a bore constituting a bearing for said annular enlargement and a transverse partition at the outer end of said bore provided with a port coacting with said needle valve.

5. A nozzle of the class described comprising a stationary T-coupling, a tubular valve carrying member fitting within the depending branch of said coupling and having an annular flange engaging the lower end thereof, a needle valve arranged within said valve carrying member and having a stem fixed at its inner end to the inner end of said valve carrying member, a nozzle member threaded for longitudinal adjustment within said valve carrying member and having a central transverse partition provided with a port coacting with said needle valve, and a packing gland threaded to said depending branch for holding 105 said valve carrying member in place and for sealing the nozzle against leakage.

6. A nozzle of the class described comprising a coupling, a tubular valve carrying member frictionally fitting within said coupling and having an annular end flange engaging the end thereof, a needle valve arranged within said valve carrying member and having a stem fixed at its inner end to the inner end of said valve carrying member, a nozzle member threaded for longitudinal 120 adjustment within said valve carrying member and having a transverse partition provided with a port coacting with said needle valve, and a packing gland threaded to said coupling for holding said valve carrying member in place and for sealing 125 the nozzle against leakage.

7. A nozzle assembly of the class described comprising a coupling having a cylindrical portion, a valve carrying member removably fitting within said cylindrical portion and having an 130 outwardly extending flange at its outer end engaging the end of the cylindrical portion, a needle valve having a stem the inner end of which is mounted in the inner end of said valve carrying member and the outer end of which is provided 140 with an enlargement within said valve carrying member and having a groove therein, the valve carrying member having a passage at its inner end communicating with the interior of the coupling, a nozzle threaded within said valve carrying member and having a bore constituting a centering bearing for the needle valve enlargement within said valve carrying member and a transverse partition with a central port for coaction 145 with said needle valve, a packing gland 150

threaded to said cylindrical portion of the coupling and having an inturned flange slidably fitting said nozzle, and a packing ring disposed between said inturned flange and the outwardly extending flange of said valve carrying member for holding the valve carrying member in place and for sealing the nozzle against leakage without interfering with the adjustability of the nozzle relative to the valve carrying member.

10 8. A nozzle assembly of the class described comprising a coupling, a valve carrying member mounted in said coupling, a needle valve having a stem the inner end of which is mounted in

the inner end of said valve carrying member and the outer end of which is provided with an enlargement within said valve carrying member and having a groove therein, the valve carrying member having a passage at its inner end communicating with the interior of the coupling, and a nozzle threaded within said valve carrying member and having a bore constituting a centering bearing for the needle valve enlargement within said valve carrying member and a transverse partition with a central port for coaction with said needle valve.
